UNITED STATES PATENT OFFICE

ALRAH B. EDWARDS AND FRANK K. RUSSELL, OF DALLAS, TEXAS, ASSIGNEES TO
STANDARD PHONOTYPE COMPANY, OF DALLAS, TEXAS, A CORPORATION OF
ARIZONA.

WRITING-MACHINE.

1,162,689.

Specification of Letters Patent.

Patented Nov. 30, 1915.

Application filed December 12, 1912. Serial No. 736,319.

To all whom it may concern:

Be it known that we, ALRAH B. EDWARDS and FRANK K. RUSSELL, citizens of the United States, residing at Dallas, in the county of Dallas and State of Texas, have invented certain new and useful Improvements in Writing-Machines, of which the following is a specification.

Our invention relates to stenographic writing machines and particularly to a ribbon feed and reverse for such machines.

The object of our invention is to provide a simple and efficient ribbon feed and reverse automatically operated through the medium of a universal bar from the striking mechanism of the machine.

We have illustrated one exemplification of our invention in the drawings, in which: Figure 1 is a top plan view of the invention applied to a stenographic writing machine, showing the ribbon feed in one position. Fig. 2 is a sectional view taken on the line $x-x$ of Fig. 1. Fig. 3 is a rear elevation of the invention. Fig. 4 is a top plan view thereof, showing the ribbon feed in the opposite position from that shown in Fig. 1. Fig. 5 is a detail of the springs forming part of the invention. Fig. 6 is a detail of the retaining dog.

Referring more particularly to the drawings, reference character 1 designates a pivoted universal bar which is oscillated toward the rear of the machine by the movement of type bars 2, each of which is in turn operated by the depression of its corresponding key lever 3, and returned to normal position by the forwardly acting impulse of the spring 4. The ribbon feed and reverse is actuated by the universal bar 1.

The striking mechanism of the machine, except as above indicated, and other related parts of the machine shown in Figs. 1 and 2 form no part of the present invention and will not here be described.

The present invention consists in the mechanism shown in Figs. 3, 4, 5 and 6. Suitably journaled in the framework of the machine is a pair of oppositely disposed spool spindles 5 which carry at the upper ends thereof the ribbon spools 6, 6'. Mounted on the other end of said spindles 5 is a pair of ratchet wheels 7, 7'. A pair of spring-pressed pawls 8, 8' engage said ratchet wheels 7, 7', said pawls 8, 8' being pivotally mounted on a pair of levers 9, 9'

provided with recesses 10 in the rearwardly extending arms thereof which engage the universal bar 1 heretofore described. The pawls 8, 8' are considerably wider than the ratchet wheels 7, 7' for the purpose of engaging a pair of adjacent cams to be hereinafter described. The levers 9, 9' are pivoted at 11 to the framework of the machine. It will be evident that each time the universal bar 1 is oscillated rearwardly or in the direction of the arrow by the striking mechanism briefly outlined above, the pawls 8, 8' will be actuated through the levers 9, 9' and the ratchet wheel 7 or 7' which is engaged by the corresponding pawl 8 or 8' is intermittently rotated while the machine is being operated. As will later appear, the ratchet wheels 7 and 7' and the correlated spools 6 and 6' are rotated in the directions of their respective arrows and then reversed. When the ribbon 12 is being wound upon the driven spool the unwinding thereof idly rotates the other spool. A pair of spring-pressed pawls 13, 13' of substantially the same width as the pawls 8, 8' serve to hold the ratchet wheels 7 against slippage during the idle strokes of the pawls 8, 8'.

The automatic ribbon reversing mechanism will now be described. A double-armed lever 14 is pivoted to the framework of the machine at 15. The arms of the lever 14 are rearwardly extended at 16 and carry at the outer ends thereof a pair of spring-pressed pivotally-mounted dogs 17, 17'. The dogs 17, 17' are adapted to bear upon the ribbon 12 on the respective spools 6, 6' and, when the ribbon is entirely unwound from the corresponding spool, to enter a recess 18, 18' in the hub portion thereof, which shifts the lever 14 for a purpose to be later described. It will be apparent that the force exerted on the dog 17 or 17' by the continued revolution of the spool after said dog has entered the notch thereof, causes the shifting of the lever 14. Just underneath the lever 14 and adjacent thereto a double-armed lever 19 is pivoted at 15. The lever 19 is provided with elongated slots 20 at each end thereof, said slots being adapted to each receive a pin 21 provided on a pair of cams 22, 22' loosely mounted on the spindles 5 adjacent the ratchet wheels 7, 7'. The cams 22 are shaped as illustrated in Fig. 4. The lever 19 is provided at one side with a forwardly extending arm 23

provided with an upturned portion 24. An arm 25 is fixed to said upturned portion 24 and passes through an apertured upturned lug 26 provided on the lever 14. The arm 25 is provided at its free end with an integral button 27. A coiled spring 28 is mounted on the arm 25 and bears against the upturned portion 24 and the lug 26, and a similar coiled spring 29 is mounted on the 10 arm 25 and bears against the lug 26 and the button 27. Conveniently pivoted to a portion of the framework of the machine is a dog 30 provided with a projection 31 adapted to enter either one of two notches 15 32, 32' provided in the extension 23, depending on the position of the lever 19, and retain said lever in the corresponding operative position until the ribbon is fed from one spool to the other. A coiled spring 33 is fixed at one end to the framework of the 20 machine and at the other end to the projection 31 and serves to hold the dog in engagement with the notch 32 or 32'.

The operation of the ribbon reversing 25 mechanism is as follows: It will be noted that in Fig. 4 the ribbon 12 has been entirely unwound from spool 6, the cam 22 has been shifted out of engagement with the pawls 8, 13 so that said pawls are impelled by their springs into engagement 30 with the ratchet wheel 7 and the pawls 8', 13' have been thrown out of engagement with the ratchet wheel 7' by the shifting of the cam 22' so that the next operation of the 35 striking mechanism will rotate the spool 6 in the direction of the arrow. While the ribbon was being unwound from spool 6 and up to the point when said ribbon was fully unwound, the parts were in the position 40 shown in Fig. 1. As the unwinding of the ribbon is fully completed, the dog 17 is impelled by its spring into the notch 18 and the lever 14 is thereby shifted to the position shown in Fig. 4. During the shifting of the 45 lever 14 the lug 26 thereon, moving rearwardly, sets up a compression in the spring 29 which in turn exerts a pressure against the button 27 and thereby forces the arm 25 rearwardly. The arm 25 carries the lever 50 19 rearwardly until the projection 31 on the dog 30 enters the notch 32. The lever 19 shifts the cam 22 into inoperative position and the cam 22' into operative position; the pawls 8, 13 thereby fall into operative position and the pawls 8', 13' are held in 55 operative position as shown in Fig. 4. The spool 6 is therefore in position to drive.

After the ribbon has been entirely fed 60 onto the spool 6 through the medium of the feed mechanism heretofore described, the dog 17' enters the recess 18', lever 14 is thereby shifted into the position shown in Fig. 1, the lug 26 moving forwardly with the said lever 14 sets up a compression in the 65 spring 28 which, bearing against the up-

turned portion 24, shifts the lever 19 into the position shown in Fig. 1, and the projection 31 is thereby forced out of the notch 32 and enters the notch 32', and the parts are thereby retained in the position shown in Fig. 1 during the feed of the ribbon from spool 6 to spool 6'. It will be seen that when the lever 19 has been shifted to the position shown in Fig. 1, the cam 22' is thrown into inoperative position and the pawls 8', 13' are allowed to assume their normal positions in engagement with the ratchet wheel 7', so that the spool 6' is adjusted to drive.

It is to be understood that the form of our invention illustrated and described is merely 80 for purpose of exemplification and that we contemplate any variations in construction within the scope of the following claims.

We claim:

1. A ribbon reversing mechanism comprising a pair of spools provided with recesses in the hubs thereof and a ribbon connected thereto, means for driving said spools, a pair of dogs adapted to alternately enter said recesses, a pair of coiled springs, 85 means connected with said dogs for alternately setting up compression in said springs, and means actuated by the compressed springs for alternately shifting the drive of said spools.

2. A ribbon reversing mechanism comprising a pair of spools having a ribbon connected thereto, means for driving said spools, a pair of cams adapted to throw said driving means into and out of engagement with said spools, a double-armed lever connected to said cams, a pair of coiled springs, mechanism connected with said spools and with said lever for alternately compressing said springs when the ribbon is 100 alternately unwound from said spools, and means actuated by the compressed springs for alternately shifting said cams.

3. A ribbon reversing mechanism comprising a pair of spools provided with recesses in the hubs thereof and a ribbon connected thereto, means for driving said spools, a pair of dogs adapted to alternately enter said recesses, a pair of cams adapted to throw said driving means into and out of engagement with said spools, a double-armed lever connected to said cams, a pair of coiled springs, means connected with said dogs and with said lever for compressing said springs when the ribbon is alternately 115 unwound from said spools and means actuated by the compressed springs for alternately shifting said cams.

4. A ribbon reversing mechanism comprising a pair of spools provided with recesses in the hubs thereof and a ribbon connected thereto, a pair of dogs adapted to alternately enter said recesses, a pair of coiled springs, a double-armed lever connected with said dogs and adapted to al- 125 130

ternately compress said springs and means actuated by the compressed springs for alternately shifting the drive of said spools.

5. A ribbon reversing mechanism comprising a pair of spools provided with recesses in the hubs thereof and a ribbon connected thereto, a pair of dogs adapted to alternately enter said recesses, means for driving said spools, a pair of cams adapted to throw said driving means into and out of engagement with said spools, a double-armed lever connected with said cams, a pair of coiled springs connected with said double-armed lever, a second double-armed lever connected 15 with said dogs and adapted to alternately compress said springs when the ribbon is alternately unwound from said spools, and means actuated by the compressed springs for alternately shifting said cams.
- 20 6. A ribbon reversing mechanism comprising a pair of spools provided with recesses in the hubs thereof and a ribbon connected thereto, a pair of dogs adapted to alternately enter said recesses, means for driving said spools, a pair of cams adapted to throw said driving means into and out of engagement with said spools, a double-armed lever connected with said cams, said lever being provided with an extension, a pair of coiled 30 springs connected with said extension and a pair of notches provided in said extension, a second double-armed lever connected with said dogs and adapted to alternately compress said springs when the ribbon is alternately unwound from said spools, means actuated by the compressed springs for alternately shifting said cams, and a spring-pressed retaining dog adapted to alternately coact with said notches to hold said cams 35 in shifted position during the feed of the ribbon in one direction.

7. A ribbon feed and reversing mechanism comprising, in combination with a universal bar, a pair of levers engaging said bar, a pair of actuating pawls pivotally mounted on said levers, a pair of ratchet wheels normally engaged by said pawls, a pair of spools mounted to rotate with said ratchet wheels and having a ribbon connected thereto, a pair of springs, means for alternately setting up compression in said springs when the ribbon is alternately unwound from said spools, and cams actuated by the compressed springs for alternately throwing said pawls into and out of engagement with said ratchet wheels.

8. A ribbon feed and reversing mechanism, comprising, in combination with a universal bar, horizontally-oscillating levers engaging said universal bar, pawls actuated by said levers, ratchet wheels actuated by said pawls, ribbon reels mounted to rotate with

said ratchet wheels and provided with notches, pawls for engaging said notches, a centrally-pivoted lever having two arms 65 and carrying said last-mentioned pawls, a second centrally pivoted lever, springs for transmitting energy from the first-named centrally-pivoted lever to the last-named centrally-pivoted lever, notches in said last-named centrally-pivoted lever, a dog for engaging said notches, and cams actuated by said last-named centrally-pivoted lever.

9. A ribbon feed and reversing mechanism comprising, in combination with a universal bar, horizontally-oscillating levers carrying pawls and actuated by said bar, ribbon reels actuated by said pawls and provided with notches, a centrally-pivoted lever carrying means for engaging said 75 notches, a second centrally-pivoted lever carrying means for engaging said first-named centrally-pivoted lever, and cams oscillated horizontally by said second-named lever.

25 10. A ribbon feed and reversing mechanism comprising reels, means for revolving said reels, a centrally-pivoted, horizontally oscillating lever actuated by said reels, a second oscillating lever, spring for actuating said second lever, said springs being actuated by said first lever, and means actuated by said second lever for engaging and disengaging said reel revolving means.

30 11. A ribbon feed and reversing mechanism comprising reels and means for revolving said reels, an oscillating lever actuated by said reels, springs actuated by said lever, an oscillating lever actuated by said springs, a bar having notches, pawl for engaging said 90 notches, said bar having a substantially straight surface between said notches whereby said bar may move easily when said pawl is forced out of one of said notches.

35 12. A ribbon feed and reversing mechanism comprising reels, means for revolving same, an oscillating lever actuated by said reels, springs adapted to be compressed by said lever, a second oscillating lever adapted to be actuated by said springs, means for 100 retaining said second lever until one of said springs is sufficiently compressed, horizontally-oscillating cams adapted to move said revolving means into and out of operation, said cams being actuated by said second 110 lever.

40 In testimony whereof we have signed our names to this specification in the presence of two subscribing witnesses.
